John Rogers.

Statuette group, the camp life.

Patented April 1, 1862.

John Rogers.

Des. 1559

John C. Rogers, of New York, N. Y.
Letter Patent No. 1559, dated April 1, 1862.

The schedule referred to in these Letters Patent and making part of the same.

Dec. 1559

To all whom it may concern:

Be it known that I, John Rogers, of the City and County of New York, and State of New York, have invented or produced a new and original design for a group of figures and I do hereby declare that the following is a full and exact description of the same, reference being had to the accompanying drawings.

The group consists of two figures in Zouave Costume playing cards on the head of a drum, and is called Camp Life.

One soldier A. of the group holds some cards in his left hand B. and with his right hand C. points to a card D. the other soldier E. has played and looks fiercely at him as if accusing him of cheating. His opponent endeavours to hide a card E. G. in each hand while he looks at his comrade with a look of injured innocence. Both figures are sitting on their knapsacks F. J. and on opposite sides of the drum K.

Having thus described my invention what I claim and desire to secure by Letters Patent, is the design for a group of statuary as hereinafter fully described and shown.

Witnesses.
